US00D780311S

(12) **United States Design Patent** (10) **Patent No.:** **US D780,311 S**
Cheney et al. (45) **Date of Patent:** **** Feb. 28, 2017**

(54) **ORTHOPEDIC IMPLANT**

(71) Applicant: **BioMedical Enterprises, Inc.**, San Antonio, TX (US)

(72) Inventors: **Daniel F. Cheney**, San Antonio, TX (US); **Mark S. Myerson**, Baltimore, MD (US); **John Kent Ellington**, Charlotte, NC (US); **Thomas J. Chang**, Santa Rosa, CA (US); **J. Chris Coetzee**, Eagan, MN (US); **Bryan D. Den Hartog**, Urbandale, IA (US); **Anish R. Kadakia**, Glenview, IL (US)

(73) Assignee: **BioMedical Enterprises, Inc.**, San Antonio, TX (US)

(**) Term: **14 Years**

(21) Appl. No.: **29/509,747**

(22) Filed: **Nov. 20, 2014**

(51) LOC (10) Cl. **24-02**

(52) U.S. Cl.

USPC **D24/155**

(58) **Field of Classification Search**

USPC **D24/155-157; D8/390**

CPC **A61B 17/0642; A61B 17/0682; A61B**

17/0644; F16B 15/06

(57) **CLAIM**

The ornamental design for an orthopedic implant, as shown and described.

DESCRIPTION

FIG. 1 is a perspective view of the orthopedic implant according to a first embodiment;
FIG. 2 is a front view thereof;
FIG. 3 is a rear view thereof;
FIG. 4 is a top view thereof;
FIG. 5 is a bottom view thereof;
FIG. 6 is a left side view thereof;
FIG. 7 is a right side view thereof;
FIG. 8 is a perspective view of the orthopedic implant according to a second embodiment;
FIG. 9 is a front view thereof;
FIG. 10 is a rear view thereof;
FIG. 11 is a top view thereof;
FIG. 12 is a bottom view thereof;
FIG. 13 is a left side view thereof; and,
FIG. 14 is a right side view thereof.

1 Claim, 10 Drawing Sheets
